UNITED STATES PATENT OFFICE.

HENRY D'OLIER, JR., OF BRIDGEPORT, CONNECTICUT.

REFLECTOR-HOLDER.

1,228,003.

Specification of Letters Patent.

Patented May 29, 1917.

Application filed March 28, 1916. Serial No. 87,159.

To all whom it may concern:

Be it known that I, HENRY D'OLIER, Jr., a citizen of the United States, residing at Bridgeport, county of Fairfield, State of Connecticut, have invented an Improvement 5 in Reflector-Holders, of which the following is a specification.

This invention has for its object to provide a reflector holder especially adapted for 10 use in connection with two-part porcelain lamp sockets which shall comprise simply a plurality of depending arms which may be either detachably or permanently secured to the upper part of the lamp socket, the lower 15 ends of the arms being provided with means for engaging a reflector and the lower part of the lamp socket acting to lock the arms in the engaging position.

With this end in view, I have devised the 20 novel reflector holder which I will now describe, referring to the accompanying drawing forming a part of this specification and using reference characters to indicate the several parts:—

25 Figure 1 is an elevation, partly broken away, showing my novel reflector holder in use;

Fig. 2 a view on an enlarged scale, partly in elevation and partly in section on the line 30 2—2 in Fig. 1, illustrating a form of the invention in which the arms are detachably secured to the cap on the upper part of the lamp socket;

Fig. 3 an inverted plan view of the cap 35 detached;

Fig. 4 a perspective view of one of the arms detached; and

Fig. 5 is an elevation illustrating a variant form in which the reflector is supported 40 independently of the porcelain parts of the lamp socket.

10 denotes the upper porcelain part of the lamp socket, 11 the lower porcelain part thereof, 12 the metallic cap which is secured to the upper part of the lamp socket, 13 a shade or reflector, and 14 the arms, which are shown as made from sheet metal. The neck of the reflector, or an extension by which it is carried, is provided with an inwardly 45 turned flange 15, which is engaged by the lower ends of the arms. The arms are shown as provided with U-shaped sockets 16 formed by bending the metal of the arms and adapted to receive the flange of the reflector. In the form illustrated in Figs. 1 to 50 55 4 inclusive, the upper ends of the arms are

bent to form L-shaped catches 17. The under side of the cap is provided with a circular recess 18 and the edge of the cap is provided with openings leading into the recess and adapted to receive the catches on the upper ends of the arms. The catches are engaged with the cap in the manner shown in Fig. 2. The arm is held horizontally and the end of the catch passed through an opening in the edge of the cap and then the arm is allowed to drop to place, the end of the L-shaped catch then engaging the outer wall of the circular recess in the cap, as indicated at the right of Fig. 2, thus retaining the arm securely in place, as it cannot be removed again without raising the arm to the horizontal position.

I have shown the holder as comprising four arms, but any other suitable number 50 may be used if preferred. Having attached the arms to the upper part of the lamp socket, the arms are grasped by the hand and are closed inward sufficiently to permit the U-shaped sockets to be passed within the 55 opening in the neck of the reflector or an extension. The arms are so shaped that when the operator removes his hand, the flange of the reflector will lie in the U-shaped sockets and the reflector will be supported by the holder. The lower part of the lamp socket is then inserted to place, through the neck of the reflector and between the arms, and is secured to the upper part of the lamp socket in the ordinary or in any 60 preferred manner. The lower part of the lamp socket when in place lies in close engagement with the inner sides of the arms and locks them in the engaging position, so that the arms cannot be moved inwardly and 65 the reflector cannot possibly be detached from the holder without first detaching and entirely removing the lower part of the lamp socket. This non-removability of the reflector without removing the lower part of 70 the lamp socket is an important feature of construction, especially in connection with large sized lamps, as it insures the safe retention of the reflector in place.

The form illustrated in Fig. 5 is intended 75 for use where it is desired to remove all strain from the porcelain parts of the lamp socket, so that even should the socket become broken the reflector would still be held in place as firmly as ever. In this form the 80 arms rest upon a disk 19 which is secured to the cap, thus entirely relieving the porcelain 85

parts of the socket from the strain of supporting the weight of the reflector. The arms may or may not be attached to the disk, as preferred.

5 Having thus described my invention, I claim:—

1. A reflector holder for two-part lamp sockets comprising a plurality of depending arms adapted for attachment to a lamp socket, said arms being provided with means for engaging a reflector, the lower part of the lamp socket acting to lock the arms in the engaging position.

10 2. The combination with a two-part porcelain lamp socket, of a holder comprising a plurality of arms adapted for attachment to the upper part of the lamp socket and having at their lower ends means for engaging a reflector, said arms being locked in engagement with the reflector by the lower part of the lamp socket.

15 3. The combination with a two-part porcelain lamp socket, of a holder comprising a plurality of arms detachably secured to the upper part of the lamp socket and having at their lower ends means for engaging inside a reflector member, and means for holding said arms outwardly for locking said arms in the engaging position.

20 30 4. The combination with a two-part lamp socket and a reflector, of a holder comprising a plurality of depending arms, means on said arms for engaging the reflector and means for detachably securing said arms to the upper part of the lamp socket, said arms normally hanging in the engaging position and being locked in the engaging position by the lower part of the lamp socket.

25 40 5. The combination with a two-part lamp socket, of a reflector holder comprising a plurality of arms adapted to be secured to the upper part of the lamp socket and provided with means for engaging a reflector, said arms normally hanging in the engaging position and being locked in the engaging position by the lower part of the lamp socket.

45 50 6. The combination with lamp socket structure comprising two parts detachable from each other, of a plurality of holder arms supported at their ends upon one of said parts and adapted at their other ends to engage within a reflector member, said arms being prevented from removal from said reflector member by the second lamp socket part.

55 60 7. The combination with lamp socket structure comprising two parts detachable from each other, of a plurality of holder arms supported at their ends upon one of said lamp socket parts and lying against the same and engaging within a reflector member at their other ends, and means for locking said arms in engaging position comprising the second lamp socket member dis-

posed within said arms and preventing their movement inwardly.

8. The combination with lamp socket structure comprising two parts detachable from each other, of a plurality of holder arms supported at their ends upon one of said socket parts and engaging at their other ends within a reflector member, the second lamp socket part being adapted for insertion between said arms to lock them in engaging position and adapted to co-act with the first socket part.

9. The combination with lamp socket structure comprising two parts detachable from each other, of a plurality of holder arms supported at their ends upon one of said socket parts and engaging at their other ends within a reflector member, the second lamp socket part adapted to be inserted longitudinally between said arms to operate as a spreader to hold said arms in engagement with and to prevent their removal from said reflector member.

10. The combination with a lamp socket member, of holder arms supported upon said socket member and extending longitudinally beyond said socket member and adapted to severally engage within a reflector member to support the same, and means adapted to be inserted longitudinally between said arms to hold them in engaging position.

11. The combination with a lamp socket member, of holder arms bent inwardly at their ends and supported upon said socket member and extending longitudinally beyond said socket member and adapted to severally engage within a reflector member to support the same, and means adapted to be inserted longitudinally between said arms to hold them in engaging position.

12. The combination with a metallic supporting cap, of a lamp socket member supported thereby, holder arms extending longitudinally along and beyond said socket member, said arms at their ends being confined by said cap, a reflector member within which the free ends of said arms engage, and means disposed within said arms and locking them in engaging position.

13. The combination with a metallic supporting cap, of a lamp socket member supported thereby, holder arms extending longitudinally along and beyond said socket member, said arms at their ends being confined by said cap, a reflector member within which the free ends of said arms engage, and a co-acting socket member detachably secured to said first named socket member in position to lock said arms in engaging position.

14. The combination with a supporting member, of holder arms supported thereon and extending longitudinally, a reflector member having an opening, said arms hav-

ing depressions at their ends receiving said reflector member, and means adapted to be inserted through said opening between said arms to lock them in engaging position.

5 15. The combination with lamp socket structure comprising two parts detachable from each other, of a plurality of holder arms supported on one of said parts and extending longitudinally beyond the same, 10 a reflector member having an opening, said arms having depressions receiving said reflector member, the second socket member adapted to be inserted through said opening between said arms to lock them in engaging position in said opening.

15 16. The combination with a cap, of a member supported thereon, a flange on said cap extending toward said member, said flange having a plurality of recesses, holder 20 arms extending longitudinally of said mem-

ber beyond the same and adapted to engage within a reflector member, said arms having inwardly and then longitudinally extending portions adapted to be inserted through said recesses. 25

17. The combination with a cap, of a member supported thereon, a flange on said cap extending toward said member, said flange having a plurality of recesses, holder arms extending longitudinally of said member beyond the same and adapted to engage within a reflector member, said arms having inwardly and then longitudinally extending portions adapted to be inserted through said recesses, and means disposed 30 within said arms locking them in engaging position. 35

In testimony whereof I affix my signature.

HENRY D'OLIER, JR.
